UNITED STATES PATENT OFFICE.

IRA A. GAY, OF CHICAGO, ILLINOIS.

VACUUM-BOTTLE CARRYING CUP CAP.

Application filed March 26, 1921. Serial No. 455,933.

To all whom it may concern:

Be it known that I, IRA A. GAY, citizen of the United States, residing at Chicago, in the county of Cook and State of Illinois, 5 have invented certain new and useful Improvements in Vacuum-Bottle Carrying Cup Caps, of which the following is a specification.

This invention relates to an improved 10 vacuum bottle carrying cup cap and has as one of its principal objects to provide a device of this character by means of which a vacuum bottle may be easily and conveniently carried.

15 The invention has as a further object to provide a cap having a handle which may be grasped for carrying the bottle to which the cap is applied and wherein, when the cap is used as a cup for hot fluids, the handle 20 will provide a means for holding the cup without burning the fingers.

And the invention has as a still further object to provide a cup cap which may be securely locked upon the vacuum bottle.

25 Other and incidental objects will appear hereinafter.

In the drawing:

Figure 1 is a side elevation showing my improved device in connection with a vacuum bottle of conventional design, the device being illustrated in section,

Figure 2 is a perspective view showing the device in detail, and

Figure 3 is a perspective view showing 35 the cap inverted to provide a cup.

At present, a case for the usual vacuum bottle is employed in order that the bottle may be conveniently handled and carried about and although vacuum bottles of the 40 type commonly known as unbreakable do not require a case, a case is, nevertheless, also usually employed in conjunction with this type of bottle to facilitate handling and carrying of the bottle. The present invention, 45 therefore, seeks to provide a means whereby the need for a case will be eliminated while, at the same time, a vacuum bottle equipped with the device may be handled and carried with entire convenience. Referring more

50 particularly to the drawing, I have shown the invention in connection with a conventional vacuum bottle including a metallic jacket or casing 10 which is formed at its upper end with a threaded neck 11 at the 55 base of which is a shoulder 12, it being ob-

served that the neck is provided with a smooth portion 13 between the threads thereon and said shoulder. In carrying the invention into effect, I employ a preferably metal cap 14 threaded to coact with the threads of the neck 11 of the casing of the bottle, the threads of the cap being preferably pressed from the wall thereof. Below said threads, the cap is provided with a smooth portion 15 to overlie the smooth portion 13 of the neck 11 while at its lower end, the wall of the cap is rolled outwardly to form a lip 16 seating against the shoulder 12. Integrally formed on or otherwise secured to the smooth portion 15 of the cap is a radial lug 17 having spaced ears and pivoted between said ears is a cam lever 18 movable to closed position lying at its outer end against the cap wall and projecting at its inner end through said wall to impinge the smooth portion 13 of the neck 11. Consequently, after the cap has been screwed down tight against the shoulder 12, the cam lever 18 may be swung to coact with the neck of the casing for locking the cap thereon so 80 that, in the practical use of the device, accidental displacement of the cap will be effectually prevented. In applying the improved cap to an ordinary vacuum bottle, the lever 18 will, when initially swung to 85 its active position, press an indentation in the portion 13 of the neck 11 and no means other than the lever will be found necessary to form the indentation. The indentation will, of course, provide a secure purchase for the 90 inner end of the lever and by screwing the cap tightly against the shoulder 12, as will, under ordinary circumstances, be commonly practiced, the lever will be moved to register with the indentation so that the lever 95 will engage in said indentation each time the cap is applied. Spanning the cap at its upper end is an upstanding handle 19 which may be integrally formed on or otherwise secured to the cap. As best 100 shown in Figure 2, the handle is provided with curved end portions which converge inwardly to the side wall of the cap and are joined by a straight flat connecting portion 20 spaced above the upper end of the 105 cap, it being observed in this connection that the connecting portion 20 lies diametrically of the cap. As will be perceived, the handle 19 may, after the cap is applied, be readily grasped for carrying the vacuum bottle so 110

that no carrying case will be necessary. Furthermore, the handle will provide a convenient means whereby the cap may be applied or removed.

Attention is now directed to the fact that when the cap is removed, the cap may be employed as a drinking cup into which the contents of the bottle may be poured. As is well known, the ordinary vacuum bottle cap, being of metal, often becomes too hot to handle when filled with hot fluids. However, the present invention effectually overcomes this disadvantage since the handle 19 may, when the cup is filled with a hot fluid, 15 be grasped for holding the cup so that the cup may be readily handled without burning the fingers. Furthermore, by forming the handle with the straight flat connecting portion 20, the handle is, when the cap is inverted to provide a cup, adapted to form 20 a base or foot for the cup so that the cup may, for instance, be rested upon a table without marring the table. I accordingly provide a highly efficient device for the purpose set forth and a cap which may be readily employed in connection with ordinary vacuum bottles without the necessity for structural change therein.

Having thus described the invention, what is claimed as new is:

1. A bottle cap including a cap body, a handle carried thereby, and pivoted locking means upon the cap body to operatively contact with the bottle for securing the cap thereon.

2. The combination with a bottle having a casing, of a cap for the bottle having threaded connection with said casing, a handle upon the cap adapted to be grasped for carrying the bottle, and a cam lever mounted 40 upon the cap and movable to impinge the casing locking the cap thereon.

3. The combination with a bottle having a casing, of a cap for the bottle detachably connected to the casing, and locking means carried by the cap to impinge the casing for securing the cap thereon.

4. The combination with a bottle, and a casing therefor, of a cap detachably connected to the casing normally housing the mouth of the bottle, and a handle upon the cap exposed for the carrying of the bottle and formed to support the cap in inverted position providing a cup.

In testimony whereof I affix my signature.

IRA A. GAY. [L.S.]
